UNITED STATES PATENT OFFICE.

HENRY WILCOX, OF NEWARK, NEW JERSEY.

DISPLAY ARTICLE.

SPECIFICATION forming part of Letters Patent No. 778,208, dated December 20, 1904.
Application filed July 12, 1904. Serial No. 216,227.

To all whom it may concern:

Be it known that I, HENRY WILCOX, a citizen of the United States, whose residence and post-office address is 74 Monmouth street, Newark, county of Essex, State of New Jersey, have invented certain new and useful Improvements in Display Articles, fully described and represented in the following specification and the accompanying drawings, forming a part of the same.

The object of this invention is to display small articles upon the counters and showcases of sales-rooms, so as to attract attention to such articles, and to support them in a convenient position for inspection and for removal when they are sold.

The greater number of supports which are provided to display small articles require a wire frame to hold them erect or a leg of some kind to support the display-body in an inclined position, like an easel; but the display-body in the present invention is made round and hollow, so that it is adapted to stand erect without any support and operates by its curved outer surface, which holds the series of articles in various relations to the eye to display the articles in a more effective and attractive manner than a flat surface.

The appearance of the display-body is rendered more attractive by flaring it more toward the base, which gives it the shape of a conical frustum. Such a shape may be readily given to the display-body by forming a single strip of pasteboard or sheet metal with the required curvature and then joining the ends of the strip together. While the strip is flat it is readily printed with a series of inscriptions with corresponding spaces, in which the articles are secured upon the surface of the body and are held in the desired relation to the inscriptions. By making such bodies of conical or flaring shape they are adapted to rest closely within one another, and a large number of such display-bodies may thus be packed together for transportation.

The invention will be understood by reference to the annexed drawings, in which— Figure 1 is a perspective view of one of the display-bodies with articles secured thereon represented as bottles of cologne; and Fig. 2

represents the curved strip *a*, from which the display-body is made by suitably bending the strip and attaching the ends together.

Eyelet-holes *b* are shown near the ends of the strip, by which the ends may be readily secured together, and inscriptions *c* are shown upon the strip, which when the display-body is finished, as shown in Fig. 1, forms an endless series of inscriptions upon the circular surface of the body. Spaces *d*, corresponding to the inscriptions *c*, are shown in Fig. 2 for applying the articles to be displayed, (shown by the cologne-bottles *e* in Fig. 1,) which are shown attached to the circular surface by wire loops *f*.

The curvature of the bodies displays the articles *e* to the eye in different positions at different points upon the body, and thus furnishes a greater interest and attraction to such articles than if mounted upon a flat surface.

The hollow circular form of the display-body obviates the necessity of any standard to support the same upon a counter or showcase, while it displays the goods in a very prominent manner. Holes *g* are shown at 75 opposite sides of the display-body near the top, in which a wire *h* may be inserted to suspend the body upon any suitable elevated support or over the flame of a gas-fixture if the body be made of material sufficiently translucent for the light to strike through the same. Such a disposition of the display-body attracts attention to it by reason of its form and location.

This display device is exceedingly cheap in 85 construction and is adapted for exhibiting a great variety of articles in drug-stores and hardware-stores and similar places where small goods are exposed on counters.

It will be noted by reference to Fig. 2 that 90 the display-body is first manufactured in a flat form, which permits any printing, designs, or ornamentation to be readily made thereon by a printing-press, and the display-bodies may be packed for shipment in flat form, in which 95 they would occupy less space than when nested. If desired, the articles which are to be exhibited may also be attached to the bodies while in the flat form to facilitate shipment, the display-bodies and articles being then fitted 100

for exhibition by merely curving the display-body and fastening its ends together by eyelets, paste, or any other suitable means.

I have made a claim to the display-body 5 consisting of a flat curved strip with inscriptions and corresponding spaces for the attachment of the articles to be displayed and also a claim to such a strip with the articles secured thereon, which may be done with great 10 advantage where articles are of non-frangible material, as nail-clippers, penknives, scissors, and other small articles of cutlery, hardware, and fancy goods.

Having thus set forth the nature of the invention, what is claimed herein is—

- 15 1. A display-body having the shape of a conical frustum provided with an endless circular series of inscriptions and corresponding spaces for articles to be displayed.
- 20 2. A display-body having the shape of a conical frustum and formed of a single curved strip with its ends suitably joined, and provided upon its exterior with an endless circular series of inscriptions and corresponding 25 spaces for articles to be displayed.

3. A display-body consisting of a single curved strip provided upon its exterior with a series of inscriptions and corresponding spaces for articles to be displayed, and adapted by merely securing its ends together to form 30 a conical frustum, whereby the display-bodies may be packed and transported in a flat condition.

4. A display-body consisting of a single curved strip provided upon its exterior with 35 a series of inscriptions and corresponding spaces with the articles to be displayed secured in such spaces, and adapted by merely securing its ends together to form a conical frustum, whereby the display-body and articles secured together may be packed and transported in a flat condition.

In testimony whereof I have hereunto set my hand in the presence of two subscribing witnesses.

HENRY WILCOX.
